7 Claims. (Cl. 23—273)

This application is a continuation-in-part of my pending application Serial No. 82,456, filed January 13, 1961.

This invention relates to improved apparatus useful for zone refining, crystal growing or zone levelling of semi-conductor rods by the known floating-zone-melting technique or process. The invention relates in particular to bearing pieces for supporting a semi-conductor rod in an evacuated envelope while being treated according to the zone-melting-process whereby the parts of the semi-conductor rod on each side of the molten zone are rotated relative to one another i.e. one end of the semi-conductor rod may be fixed and the other end rotated; each end of the rod may be rotated in opposite directions, or the rod portions may be rotated in the same direction at different speeds.

Among the advantages of the relative rotation of the rod sections in crystal growing are: improved thermal symmetry, and uniform distribution of the material constituents in the finished crystal. These two advantages are particularly important for III/V semi-conductor compounds of high specific gravity and having a volatile constituent, for example, gallium arsenide. However, relative rotation of semi-conducting rod section must be carried out under adverse conditions in a highly reliable manner since the surface tension of the molten zone is easily disturbed. For example, the surface tension in the molten zone of III/V compounds such as gallium arsenide, which has a high density (5 grams per cubic centimeter), can be overcome by unsymmetrical thermal conditions alone and certainly by vibrations or chatter set up in a bearing during rotation or by allowing the rod sections to imperceptably shift laterally relative to one another.

Another consideration must also be taken into account in providing apparatus for rotatively suspending gallium arsenide semi-conductor crystals during zone-melting treatment due to the volatile nature of gallium arsenide at molten temperature, i.e. arsenic evaporates and separates from the melt at said temperature. It is important therefore to conduct gallium arsenide crystal growth in a controlled atmosphere and thus provide an equilibrium atmosphere at the required temperature and pressure. Since stirring also provides an advantage in this regard it is imperative to provide bearings for the rotatable holder connected with the semi-conductor which are not adversely affected by the corrosive arsenic vapor or are shielded from contact with said vapor to avoid bearing vibration, chatter or lateral movement of a bearing supporting the rotating portion of the semi-conductor rod.

Heretofore, attempts to overcome the problems outlined above consisted of passing a shaft through a wall of the envelope containing the material to be treated and sealing this passage while allowing the shaft to rotate therein. In view of the temperature to which the seal is subjected (600° C.) and the limitation that it cannot have an adverse effect on the semi-conductor material, graphite is extensively used. However, where arsenic vapors are generated the graphite seal is not as reliable as required.

2

Attempts have been also made to overcome the above noted problems by the use of magnets which both suspend the semi-conductor within an envelope and at the same time cause relative rotation between the rod portions separated by the molten zone. While successful, these magnetic systems are quite complex as the magnetic field must be highly stabilized to prevent even the slightest movement which is sufficient to rupture the molten zone.

Accordingly an object of this invention, is to provide 5 a simple, inexpensive and highly reliable apparatus to overcome these problems, a presently preferred embodiment of which is illustrated in the accompanying drawing.

Referring to the drawing:

FIG. 1 illustrates an arrangement according to the 10 prior art.

FIG. 2 shows a bearing piece according to an embodiment of the invention wherein the semi-conductor rod is suspended and driven from above.

FIG. 3 shows a bearing piece according to the invention 15 wherein the semi-conductor rod is held and driven from its lowermost end.

FIGS. 4a and 4b are diagrammatic representations visually explaining the operation of the device according to the invention.

FIG. 5 is a view of an apparatus for treating semi-conductor material in which the bearing piece of FIG. 2 is utilized.

FIG. 6 is a view similar to FIG. 5 wherein the bearing 20 piece according to FIG. 3 is utilized.

FIG. 7 is a view of an alternative arrangement for connecting the bearing shaft with the upper ball race of FIG. 2.

FIG. 8 is a view of an alternative arrangement for connecting the bearing shaft and semi-conductor rod.

As seen in FIG. 1 a semi-conductor rod 2 is supported 25 between holders 3, 3' within an evacuated and sealed envelope 5. The upper rod portion and the lower rod portion are separated by a molten zone 1 which traverses the rod from end to end as the inductance coil 21 moves axially. Rotation of one rod section may be imparted by magnetic agency in known manner (not shown).

As seen in FIGS. 2 and 5 a rod 2 of semi-conductor material is held in a vertical position between quartz glass holders or clamps 22, 22' within an envelope 5 of 30 quartz glass. The clamp 22 is connected with rotatable shaft 9 which passes through capillary tube 8 of quartz glass. The tube 8 and the lower ball bearing race 10 are supported within the envelope 5 by means of a quartz glass holder or attachment piece 23. The lower race 10 may be detachably secured with the piece 23 in any suitable manner. The upper bearing race 11 is secured to the shaft 9 at 12 and therefore rotates with the shaft 9 by virtue of the magnets 31, 33 arranged as shown in FIG. 5 or in any other suitable arrangement. An alternative detachable connection between the shaft 9 and upper race 11 is illustrated in FIG. 7 and will be fully described in connection therewith. The upper and lower bearing races 10 and 11 are separated by glass spheres 13 held in a quartz guide ring 14. All the parts of the bearing 35 piece including shaft 9 are preferably made of quartz. It will be apparent also that the skirt portion 7 of attachment piece 23 is accurately ground as is the adjacent inclined surface of the envelope 5 to prevent any motion therebetween and thus accurately locate the shaft 9 coaxial with the axis of the fixed semi-conductor holder 3' and associated clamp 22'.

The bearing piece 10-14 is made for quick and easy 40 dismounting for cleaning purpose when necessary. It has been found that lubrication is unnecessary for a bearing as above described.

As indicated in FIG. 4a when the center of gravity 17

of the system acts on the axis of shaft 9 the bearing forces 15, 16 are uniform. If the application of gravity 17 is shifted from this location as indicated in FIG. 4b the forces acting on the bearing are not evenly distributed; nevertheless, the shaft 9 is held firmly by the bearing in its original or aligned position by virtue of the bearing 10-14 and the liquid zone 1 is not disturbed. In this connection and having reference to FIG. 5 it is noted that the ground surface of the skirt 7 of attachment piece 23 and abutting portion of envelope 8 supporting the shaft 9 provide sufficient friction under such conditions to prevent displacement of the shaft 9 or attachment piece 23 relative to the envelope 5.

It should be noted that the glass bearing 10-14 can be accurately manufactured in known manner. Thus, the spheres 13 can be formed from quartz drops and polished between glass plates. The apertures or bore through the bearing races and the ring guide can be accurately made by supersonic drills and polished by known techniques also. The drive for rod 9, and hence the upper portion 2 of the semi-conductor rod 2, 2', is provided by magnets 31 attached to the upper end of shaft 9 and magnets 33 driven by a motor 39 as indicated in the drawing. Of course, any suitable arrangement other than that illustrated may be utilized.

As seen in FIGS. 5 and 6 the apparatus is suitably located between upstanding resistance type electric heaters which heat the entire envelope to the required temperature.

The alternative arrangement previously mentioned is illustrated in FIGS. 3 and 6 wherein the rod 2, 2' of semi-conducting material is held between suitable clamps 22, 22' and supported in a point bearing located below the rod 2, 2'. In this arrangement the shaft to be rotated is designated 9' and is operatively associated with any suitable magnetic arrangement such as indicated in FIG. 6 which is similar to that illustrated in FIG. 5.

The shaft 9' projects beyond the capillary sleeve 8 within the bulbous attachment piece 18 and the accurately ground point 19 of this shaft abuts a planar supporting surface 20 of soft material, such as copper, into which the point 19 can penetrate a small distance to prevent lateral movement thereof. As disclosed above in connection with FIG. 5, the bulb 18 is ground and accurately positioned within the envelope 5 by the converging portion of envelope 5 adjacent the diverging portion of bulb 18.

It will be readily apparent from the foregoing that the bearing pieces seen in FIGS. 2 and 3 and the semi-conducting rod are readily assembled and placed with the envelope 5 which is then sealed in known manner and evacuated or any desirable atmosphere created therein. It will also be apparent that both bearing pieces may be utilized together in a single envelope if desired.

In the operation of the embodiment shown in FIGURE 5, one of the semi-conductive rods 2, 2' separated by the liquid zone 1 is rotatably arranged while the other is held against rotation. The semiconductive rod 2 is secured to rotatable shaft 9 by means of a clamping device 22 known per se. The supporting rod 9 is passed through a capillary 8 which is held by a tubular quartz plug 23 having a grounded piece 7. A lower bearing shell 10 is secured on the quartz plug 23 likewise by means of ground abutting surfaces. Between bearing race 10 and upper bearing race 11, balls 13, are maintained spaced apart in the usual manner by means of a guide ring 14.

The supporting rod 9 is passed in a gas-tight manner not only through the quartz capillary 8, but also through the bearing race 10. The supporting rod 9 is secured to the bearing race 11 at 12 in any suitable manner.

A soft-iron piece or a magnet 31 is secured to the end 29 of supporting rod 9 projecting from the bearing shell 11. In front of magnet 31 at a certain distance therefrom is another magnet 33 which is arranged through a

supporting arm 35 on a shaft 37, for example of an electric motor 39. When the shaft 37 of the motor 39 rotates, the magnet 33 moves along a circular path around the supporting rod 9, magnet 31 is thus taken along by magnet 33, so that the supporting rod 9 is rotated.

The quartz plug 23 is placed with its ground skirt 7 in the quartz tube 5 in a fitting manner. As in FIG. 1 the quartz tube contains another supporting shaft 3' to which the lower end 2' of semi-conductive rod, separated from upper end 2 by the liquid zone 1 is secured by means of clamping device 22'. The high frequency coil 21 is movable in any suitable manner relative to quartz tube 5.

The operation of the embodiment of FIG. 6 will be apparent from the foregoing.

Referring now to FIGS. 2 and 7 it will be seen that the upper race 11 of the ball bearing may be connected to the quartz shaft 9 by a suitable glass weldment 12 or by the use of a quartz glass sleeve 50 as seen in FIG. 7. The sleeve 50 may be fixedly connected to the rod and removably connected to the upper race by means of flanges 51 which are accurately ground to define a plane perpendicular with the longitudinal axis of the shaft 9. The ground surface of the flange 51 bears on the upper race 11 which is also roughened to provide a driving connection for shaft 9.

It will be seen from FIG. 8 that, in addition to the known clamp 22, 22' illustrated in FIGS. 5 and 6 for holding the semi-conducting rod, the shafts 9, 9' may be provided with a bore 60 for receiving one end of the rod 2 which is pinned in place through the horizontal bores 61.

The foregoing presently preferred embodiments of the invention are given by way of illustration and example. Many changes in the embodiments shown are within the skill of the art and such are contemplated within in the scope of the subjoined claims.

What is claimed is:

1. Apparatus for treating semi-conductor material comprising: an envelope member having a first diameter and a second diameter interconnected by a converging wall section, a bearing piece, a holder, said holder having a concentric capillary tube therein and a tapered portion for fitting within said converging wall portion, a shaft concentric with and extending axially of said capillary tube, a ball bearing having one race supported on said holder and the other race secured to said shaft, magnetic means for rotating said shaft, and means to secure a semi-conductor rod on said shaft at one end and a fixed support secured to said envelope at the other end of said semi-conductor rod; said holder dividing said envelope into first and second discrete compartments, one of which contains said semi-conductor rod.

2. Apparatus for treating semi-conductor material comprising: an envelope member having a converging wall section, a bearing piece including a holder having a tapered skirt portion for supporting said bearing piece at said converging wall portion, a capillary tube concentric with and extending axially of said holder, a shaft within said capillary tube, a ball bearing having one race supported on said holder, a skirt member connected with said shaft, said skirt member having a flange frictionally connecting said shaft with the other race of said bearing, magnetic means to rotate said shaft and means to secure a semi-conductor rod on said shaft at the end remote from said skirt and the other end of said rod to a second holder means within said envelope; said holder dividing said envelope into first and second compartments, one of which contains said semi-conductor rod.

3. Apparatus according to claim 2 wherein said means for securing said semi-conducting rod to said shaft comprises a central bore in said shaft receiving one end of said rod, said rod and said shaft being provided with a horizontal bore adapted to receive a pin securing said rod within the bore of said shaft.

4. Apparatus for treating semi-conductor material

comprising: a glass envelope member having a converging wall section, a glass bearing holder having a concentric capillary tube therein, said holder having a tapered skirt portion engaging said wall section, a lower glass bearing race supported on said holder, a glass shaft concentric within said capillary tube and connected to said lower bearing race, one end of said shaft being removably secured with a glass upper bearing race by means of a glass thimble having a flange frictionally engaging said upper bearing race, and glass ball bearing means intermediate said races; magnetic means for rotating said shaft, and means for connecting a semi-conductor with said shaft at one end, and a fixed holder connected to the other end of said rod and secured in said envelope; said holder dividing said envelope into first and second compartments, one of which contains said semi-conductor rod.

5. Apparatus for zone melting semi-conductor rod material comprising a closed tubular envelope member, upper and lower shaft members for supporting a semi-conductor rod therebetween and associated bearing means for each said shaft member; said upper bearing means comprising a capillary tube concentrically surrounding a portion of said upper shaft, a holder supported within said envelope and supporting said capillary tube, a fixed bearing shell supported at the upper end of said holder, a rotatable bearing shell coaxially spaced from said fixed bearing shell and a ball bearing race intermediate said fixed and rotatable shells, said rotatable bearing shell being detachably connected with the upper end of said upper shaft member, said lower bearing means comprising a second capillary tube concentrically surrounding a portion of said lower shaft, a second holder supported within said envelope and supporting said second capillary tube, one end of said lower shaft having a pointed bearing and

operatively associated with a supporting surface of said second holder.

6. Apparatus for zone melting semi-conductor materials comprising: an envelope member having a first diameter and a second diameter interconnected by a converging wall portion, a holder member having a concentric capillary tube therein and a tapered wall portion for fitting within said converging wall portion, said holder dividing the space within said envelope into first and second discrete compartments, a driven shaft in said capillary tube extending from said first compartment into said second compartment, bearing means connected with one end of said shaft, and means for connecting a semi-conductor rod to the other end of said shaft; whereby a corrosive gaseous atmosphere in one said compartment is sealed from entry into the other said compartment.

7. Apparatus for zone melting semi-conductor materials according to claim 6 wherein said driven shaft comprises a point bearing shaft having a magnet attached thereto and associated magnetic means for driving said shaft.
